UNITED STATES PATENT OFFICE.

HOWARD L. BUDD, OF BROOKLYN, NEW YORK, ASSIGNOR TO FRIEDMAN SILVER CO., INC., OF BROOKLYN, NEW YORK, A CORPORATION OF NEW YORK.

DESIGN FOR A BORDER STRIP.

Application filed July 30, 1928. Serial No. 27,626. Term of patent 7 years.

To all whom it may concern:

Be it known that I, HOWARD L. BUDD, a citizen of the United States, residing at the borough of Brooklyn, county of Kings, city and State of New York, have invented a new, original, and ornamental Design for a Border Strip, of which the following is a specification, reference being had to the accompanying drawing forming part thereof.

Fig. 1 is a top plan view of a border strip embodying my new design and as applied to a tray which is shown in dotted lines.

Fig. 2 is a side view of the same.

Fig. 3 is a top plan view of a fragmentary portion of the border strip on an enlarged scale.

I claim:

The ornamental design for a border strip as shown and described.

HOWARD L. BUDD.
